Des. 521

Thomas Law of New York, N.Y.

Assignor to

Ever Chapman of same place

Letters Patent No. 521 Dated Nov. 9th 1852

The schedule referred to in these Letters Patent and making part of the same

To all to whom these Presents shall come:

Be it known that I, Thomas Law, of the City, County and State of New York, have invented and made, a new and ornamental design for a Pedestal and Column; And I do hereby declare that the following is a full, clear and exact description thereof, reference being had to the annexed drawing making part of this specification, wherein Fig 1 is a plan of the pedestal, & Fig 2 is an elevation of the pedestal & column

It will be evident that the pedestal & column may be attached together by any convenient means, and also that they may be used as the stand for a camera, as a music stool or stand, as a head rest for daguerreotype operators, or for any other purpose to which they may be available.

The design on the pedestal is suitable for a stand of three or more points, and is composed of a human face in alto relief at the point of each foot combined with scrolls, grapes and leaves extending towards the centre. The junction of the design on each foot may be formed solid, or if desired to be of less weight, this part may be left as open work as shewn.

The column is to be formed with the ornamental base, ornamental shaft, and capitol as shewn, and to make the column lighter the shaft may be perforated as shewn, the ornamental design still remaining the same.

What I claim and desire to secure by

Letters Patent, is

The ornamental design on the pedestal consisting of the combination of the grapes, leaves, scrolls, and face in alto or basso

relied as shewn.

And also the ornaments for the base, shaft, and capitol
of the column herein described & shewn in Fig. 2. of the accompanying drawing.

In testimony whereof I have hereunto set my signature
this twenty seventh day of September one thousand eight hundred and fifty-two.

Witness,

Lemuel W. Terrell }
W. T. Rayland }
